UNITED STATES PATENT OFFICE.

DAVID O. JOINVILLE, OF DETROIT, MICHIGAN.

DESIGN FOR A FILTERING VESSEL.

SPECIFICATION forming part of Design No. 33,174, dated September 4, 1900.

Application filed February 26, 1900. Serial No. 6,849. Term of patent 7 years.

To all whom it may concern:

Be it known that I, DAVID O. JOINVILLE, a subject of the Queen of Great Britain, residing at Detroit, in the county of Wayne and State 5 of Michigan, have invented and produced a new and original Design for Filtering Vessels, of which the following is a specification, reference being had therein to the accompanying drawing, in which my filtering vessel is shown 10 in perspective.

As shown in the drawing, the leading or material feature of my design consists in the peculiar outline and configuration of the filtering vessel, in which A is the cylindrical body 15 portion, open on top, B is a gradually-rounding lower portion, which by means of a re-

verse curve merges into the cylindrical neck portion C, and D is an inversely-curved nozzle-shaped portion of smaller diameter extending from the lower end thereof and open 20 at its lower end.

Having thus fully described my invention, what I claim as new, and desire to secure by Letters Patent, is—

The design for a filtering vessel, substantially as herein shown and described. 25

In testimony whereof I affix my signature in presence of two witnesses.

DAVID O. JOINVILLE.

Witnesses:

OTTO F. BARTHEL,
JOS. A. NOELKE.
